STAPLING OR DISCONTINUOUS WIRE STITCHING MACHINE

John Irving Nasmith and Wilfred Kirby, London, England, assignors to Vickers-Armstrongs Limited, Westminster, England, a British company

Application March 5, 1932, Serial No. 596,960
In Great Britain May 30, 1931

12 Claims. (Cl. 1-2)

This invention relates to stapling or discontinuous wire stitching machines and has particular reference to the mechanism for cutting the wire which is fed into the machine, so as to provide the separate portions or lengths required to form the staple. In wire stitching machines of the kind referred to as heretofore constructed, one of the cutting knives or members is stationary during the operation of the machine, and the other and movable knife is directly carried by the member used for forming the cut length of wire into a staple, or by a separate member provided for the purpose, the cutting operation in either case being effected or performed by the timed actuation of the member carrying the knife. The actuated or movable knife is generally a plain steel blade which is ground when required, but constructions are known whereby a knife may be angularly moved or rotated about its fixing or mounting in order to provide a new cutting edge without re-grinding. In order to make this adjustment, however, it is necessary to remove or dismantle a portion of the machine. The chief object of the present invention is to provide improved cutting-off mechanism for machines as above referred to, which enables adjustments of the actuated or movable knife to be readily effected and also permits of a wide range of adjustments being made.

According to this invention the actuated or movable knife is so mounted and connected with its actuating mechanism that it can be readily adjusted by longitudinal or endwise movement to present a new portion of the cutting edge without the use of any tool and without dismantling or removing any part of the mechanism. According to a further feature of this invention, the knife is provided with a plurality of cutting edges each of which can be brought into operation as required by merely changing or reversing the position of the knife, this being accomplished without dismantling or removing any part except the knife itself. The adjustment above mentioned to bring a new portion of the cutting edge into use can be effected for each cutting edge when it is in the operative position. The said movable knife may be angularly movable to effect the cutting operation, for which purpose it may be pivotally mounted at one end and connected with a vertically movable actuating member at its other end. In order to bring a new portion of the cutting edge into use when required, the pivotal point can be adjusted to change the longitudinal disposition of the knife and its operative cutting edge relatively to the

cutting position, and the connection of the knife with the actuating member is such that the knife is slidably moved when the pivot point is adjusted as aforesaid. Further, the connection of the knife with its actuating member enables the knife to be readily separated from this member; for example, the end of the knife may merely project into a slot in the actuating member from which it can be readily withdrawn, whilst the other and pivoted end of the knife may be easily disconnected from the pivot about which it is angularly moved, so that by separating the knife from its actuating member and its pivot and reversing its position either transversely or longitudinally, any one of the several cutting edges can be placed in the operative position in which the aforesaid adjustment can be made, to present a new portion of the operative cutting edge as and when required.

In order that the said invention may be clearly understood and readily carried into effect, the same will now be more fully described with reference to the accompanying drawing, in which:—

Figure 1 is a front view of one construction of the cutting mechanism according to this invention.

Figures 2 and 3 are reverse or opposite side views illustrating the movable knife in different positions.

Figure 4 is a perspective view of the movable knife.

A represents the actuated or movable knife which as shown more particularly in Figure 4 is provided with cutting portions A¹, A², A³, A⁴ on its upper and lower edges, the cutting portion A¹ being shown in Figures 2 and 3 in the operative or cutting position. The said knife A is also provided with holes A⁵ adjacent to its ends A⁶, which latter are enlarged and rounded as shown, for the purpose hereinafter referred to. B indicates the stationary knife or cutting member having an aperture or passage B¹, through which the continuous length of wire is fed to the cutting position. C represents the vertically movable actuating member that imparts the necessary movement to the knife A to enable the latter to effect the cutting operation. D represents a fixed part of the machine frame in which the knife actuating member C and also the staple forming member D¹ (which latter forms no part of the present invention) are slidably mounted, both the members C and D¹ being covered at the front by a plate D² that may be screwed or otherwise attached to the frame D. In the example

shown, the knife actuating member C is vertically moved in the machine frame by means of a rotary cam plate C¹ against which bears a roller C² carried by the upper end of the knife actuating member C, the said cam plate during its revolution serving to push the actuating member downwardly against the action of a spring (not shown) that maintains the roller C² at all times in contact with the cam plate and also causes the return or upward movement of the actuating member. The lower end of the actuating member C is slotted at C³ to receive either of the enlarged and rounded ends of the movable knife A, the other end of the latter being pivotally attached by means of a removable pivot or stud E¹ to the bifurcated lower end of a lever E which is pivotally mounted at E² on a lug D³ projecting from the aforesaid cover plate D² secured to the machine frame. The removable pivot E¹ can be readily inserted in holes in the bifurcated lower end of the lever E and in either of the holes A⁵ in the knife A and it is held in place by a light flat spring E³ which is carried on the lever and can be readily displaced to permit of the pivot E¹ being withdrawn for the purpose of enabling the knife A to be quickly separated or disconnected from the lever E. The upper end of the lever E is bifurcated to embrace the outer end of an adjusting screw F that is threaded into the cover plate D² and is provided with a head F¹ and an abutment F², between which the upper end of the lever E is located as shown. The screw head F¹ may be provided with a milled edge or may be otherwise formed to enable the screw to be readily rotated and axially moved further into or out of the cover plate to vary the angular position of the lever E to which the knife A is attached by the pivot pin E¹.

When the knife actuating member C is moved downwardly by the aforesaid cam plate C¹ against the action of the spring as hereinbefore referred to, the knife A which fits at one end in the slot D³ in the said member C as aforesaid, is angularly moved on the aforesaid pivot pin E¹ carried by the arm E so that the cutting portion A¹ of the knife traverses the aperture B¹ in the fixed knife or cutting member B and thus severs the wire which is fed through this aperture. The enlarged rounded end A⁶ of the cutting knife that fits in the slot C³ in the actuating member C, permits of free angular movement of the knife when the actuating member is vertically moved and this method of connection also enables the knife to be slidably moved in the slot and to be readily disconnected from the actuating member by merely withdrawing the enlarged end A⁶ from the said slot. For the purpose of enabling a fresh portion of the operative cutting edge of the knife A to be brought into use, the aforesaid adjusting screw F is rotated to the extent required so as to change the angular position of the aforesaid lever E, thus altering the position of the pivot E¹ and changing the longitudinal disposition of the knife and its operative cutting edge relatively to the aperture B¹ in the fixed knife B through which the wire is fed. In this manner the entire length of the operative cutting edge can be utilized as a result of adjusting the screw F as aforesaid, without the use of a tool or implement of any kind and without removing any part. The adjusting screw F may be locked in the position to which it is set by any appropriate means, for example, by a spring detent (not shown) that may engage with the milled edge or other part on the screw head F¹ so as to retain the lever E and the knife A in

the required positions. In order to enable another cutting edge or portion to be used, the knife A is completely disconnected from the lever E by removing the pivot E¹ in the manner aforesaid, whereupon it can be withdrawn or disconnected from the actuating member C. The knife can then be replaced in the reverse position transversely so as to bring the cutting edge A⁴ into the operative position. By changing or reversing the position of the knife longitudinally, the cutting edges A² and A³ at the other end of the knife are placed adjacent to the fixed knife B and either of these cutting edges can be brought into the operative position by transverse reversal of the knife. Thus any one of the four cutting edges can be readily brought into use when required, and the adjustment by means of the aforesaid screw F can be effected for each of the cutting edges when in the operative position, so that the entire length of each cutting edge can be used. Instead of providing a separate actuating member for operating the knife as herein described and illustrated, the knife may be actuated by the vertically movable staple forming member or by a part connected therewith.

What we claim and desire to secure by Letters Patent of the United States is:—

1. Cutting mechanism for a machine of the kind referred to, comprising a movable and rockable knife bar, actuating mechanism for rocking the knife bar and means whereby the rocking knife is freely connected with its actuating mechanism so that it can be slidably adjusted by longitudinal or endwise movement of the knife bar to bring a new portion of the cutting edge into the cutting position without the use of a tool and without dismantling or removing any part of the machine or mechanism.

2. Cutting mechanism for a machine of the kind referred to, comprising a rockable knife bar having a plurality of oppositely disposed cutting edges, actuating mechanism for the rocking knife and means whereby the knife can be disconnected from its actuating mechanism by merely withdrawing it by the naked hand to enable it to be reversed to bring a different cutting edge into the operative position.

3. Cutting mechanism for a machine of the kind referred to, comprising a knife-bar detachably mounted at one end for angular and pivotal movements, the knife having a plurality of cutting edges, said mounting being detachable in such a way as to enable any one of the cutting edges to be brought into operative position, and a vertically movable actuating member for the knife-bar with which the other end of the knife-bar is longitudinally slidably connected to permit adjustment.

4. Cutting mechanism for a machine of the kind referred to, comprising a knife having a plurality of cutting edges which is angularly movable about a pivot, means for moving the said knife about its pivot and means for adjusting the pivot to vary the longitudinal position of the knife in relation to the cutting position, said longitudinal adjustment bringing a fresh portion of the cutting edge into the cutting position.

5. Cutting mechanism for a machine of the kind referred to, comprising an actuated knife, a lever mounted on a fixed part of the machine or mechanism and connected with one end of the said knife, a vertically movable actuating member connected with the other end of the knife and means for angularly adjusting the said lever to vary the position of the pivot and the knife.

6. Cutting mechanism for a machine of the kind referred to, comprising an actuated knife, a lever mounted on a fixed part of the machine or mechanism and connected with one end of the said knife, a vertically movable actuating member connected with the other end of the knife, means for angularly adjusting the said lever to vary the position of the pivot and the knife, and means whereby the knife pivot is readily removable to enable the knife to be disconnected from the said lever without the use of a tool. 80
7. Cutting mechanism for a machine of the kind referred to, comprising a knife having a plurality of cutting edges and angularly movable about a pivot at one end of the knife, a vertically movable actuating member, a connection between one end of the said knife and the vertically movable member to permit of slidable movement or adjustment of the knife relatively to the member, and means for moving the knife pivot so as to adjust the longitudinal position of the said knife, relatively to the cutting position, the longitudinal adjustment bringing a fresh portion of the cutting edge into cutting position. 85
8. Cutting mechanism as in claim 7, in which the said vertically movable member is provided with a slot to receive the end of the knife remote from its pivotal connection. 90
9. Cutting mechanism for a machine of the kind referred to, comprising an actuated knife, a vertically movable member for angularly moving said knife about a pivot, a lever carrying said pivot, said lever being pivotally mounted on a fixed part, an adjusting screw engaging with the said lever and adapted to be operated to vary the position of the lever and the said pivot to adjust the knife in relation to the cutting position. 95
10. Cutting mechanism for a machine of the kind referred to, comprising a movable knife, a pivot for said knife, a pivoted lever carrying said pivot, the end of the knife remote from the pivot fitting in a slot in the said actuating member, and an adjusting screw for engaging with said lever to vary the position of the knife in relation to the cutting position. 100
11. Cutting mechanism for a machine of the kind referred to, comprising a movable knife having a plurality of cutting edges, a pivot for said movable knife, a pivoted lever carrying said pivot, the end of the knife remote from the pivot fitting in a slot in the said actuating member, and an adjusting screw for engaging with said lever to vary the position of the knife in relation to the cutting position, and readily displaceable means whereby the pivot can be removed without the use of a tool to enable the knife to be reversed to bring a different cutting edge into the operative position. 105
12. For use in cutting mechanism for a machine of the kind referred to, a knife provided with cutting portions on its upper and lower edges adjacent to the ends where pivot holes are provided, the said ends being enlarged and rounded. 110
